UNITED STATES PATENT OFFICE

152,196

DESIGN FOR A COMBINATION KEY HOLDER AND BOTTLE OPENER

Arthur R. Glidden, Seattle, Wash.

Application May 23, 1947, Serial No. 139,244

Term of patent 3½ years

(Cl. D17—14)

To all whom it may concern:

Be it known that I, Arthur R. Glidden, a citizen of the United States and a resident of Seattle, in the county of King and State of Washington, have invented a new, original, and ornamental Design for a Combination Key Holder and Bottle Opener, of which the following is a specification, reference being had to the accompanying drawing, forming a part thereof.

In said drawing,

Figure 1 is a front elevational view showing my new design of a combination key holder and bottle opener.

Fig. 2 is a top plan view thereof; and

Fig. 3 is an underside plan view thereof.

I claim:

The ornamental design for a combination key holder and bottle opener, substantially as shown.
ARTHUR R. GLIDDEN.
